UNITED STATES PATENT OFFICE.

GEORGE W. DITHRIDGE, OF NEW YORK, N. Y.

BEAM OR GIRDER.

SPECIFICATION forming part of Letters Patent No. 430,840, dated June 24, 1890.

Application filed August 28, 1889. Serial No. 322,177. (No model.)

To all whom it may concern:

Be it known that I, GEORGE W. DITHRIDGE, of the city, county, and State of New York, have invented an Improvement in Beams or 5 Girders, of which the following is a specification.

My invention relates to beams or girders adapted for use in buildings or elevated-railway structures and to sills or side beams for 10 railway-car bodies.

My invention consists in a beam or sill composed of upper and lower tubes having fins or ribs made integral therewith, there being at intervals straps and bolts with central 15 stay-blocks for connecting said tubes together to form the beam or sill.

In the drawings, Figure 1 represents a cross-section of one form of my improved beam or sill, and Figs. 2 and 3 elevations of the straps 20 shown in Fig. 1. Figs. 4, 5, 6, 7, and 8 represent modified forms of my improved beam or sill; and Fig. 9 is a section at the line $x-x$ of Fig. 7.

My improved beam or sill is composed of 25 upper and lower or edge tubes $a a'$. These tubes, as shown in Fig. 1, are in cross-section an elongated oval or pear shape, and they are provided with fins or ribs $b b'$, formed integral or in one piece with said tubes. These 30 tubes I prefer to make of Bessemer steel without joint or weld and of one piece of metal.

I employ straps $c d$ of any desired width, which straps I prefer to form from bands of steel bent up to shape, and it will be noticed 35 from Figs. 2 and 3 that said straps $c d$ are exactly alike or the counterparts of each other, said straps in use being placed in opposite directions, so that the smaller end of the strap c passes within the larger end of 40 the strap d , and the smaller end of the strap d passes within the larger end of the strap c , and said straps are slipped along over the edge tubes $a a'$ into place, and I provide stay-blocks at e between the abutting ends of the 45 fins or ribs $b b'$ and bolts f to draw up and apply tension to the straps $c d$ in holding the tubes $a a'$ together and forming the beam or sill.

It will be noticed in Fig. 4 that the tubes $a a'$ are of similar shape to those in Fig. 1, 50 except that they are provided with side flanges 3 4, and that the straps $c' d'$ are adapted to pass around these flanges and lap. The cen-

tral stay-bars e in this figure have grooved edges at 5 to receive the ends of the fins or ribs $b b'$.

The beams or sills shown in Figs. 5 and 6 have tubes $a a'$, that are elongated oval or pear shaped, with fins $b b'$, slotted stay-blocks e , and connecting-bolts f , the fins or ribs in Fig. 6 being two-part or divided. In these 60 two figures the straps are interlocking—that is to say, there are circular end portions 14 15 around the tubes $a a'$ and having return-bends or hooks at 6. These straps are alike. The side straps $c^2 d^2$ are also alike and are 65 made with return-bends or hooks 7, which interlock with the return-bends 6, and the bolts f serve to draw these parts tightly together to form the beam or sill.

In Figs. 7 and 8 the tubes $a a'$ are round 70 and provided with fins $b b'$ integral therewith, and there are also stay-blocks e and connecting-bolts f .

In Fig. 7 the straps that tie the tubes together to form the beams are of somewhat 75 modified form from those heretofore described, there being straps $c^3 d^3$ at the two sides of the beam, the straps $c^3 d^3$ being connected in one instance by a short strap m , with interlocking ends 8 9, or with simply 80 interlocking ends 10, either of which forms of construction may be employed. The central portions of the straps $c^3 d^3$ are shown convexed or arching at $k l$ and ribbed at 11 12, Fig. 9, the bolt f passing through the curved 85 portion and acting against the same in straining the strap, and in practice the parts of the straps at the sides of the fins will not quite touch said fins, thereby allowing space for drawing up the plates. This is also the case 90 with the construction shown in Fig. 8.

The straps $c^4 d^4$ and the end portions 14 15 shown in Fig. 8 are similar to those shown in Figs. 5 and 6, except that the interlocking hooks are modified and shown in two different forms, either of which is available and 95 equally effective.

My improved beam or sill is strong and easily made, and is adapted for use in buildings or railway structures, and especially for 100 the side and end sills of railroad-cars, such as freight, coal, and platform cars.

I claim as my invention—

1. The beam or sill composed of upper and

lower edge tubes having fins or ribs integral therewith and blocks between their fins or ribs, and straps and bolts for connecting such tubes together to form the beam or sill, substantially as set forth.

2. The combination, in a beam or sill, with the tubes *a a'*, having fins or ribs *b b'* made integral therewith, of the encircling and interlocking straps *c d*, the central stay-blocks *e*, and the bolts *f*, substantially as set forth.

3. The combination, in a beam or sill, with the tubes *a a'*, having fins or ribs *b b'* inte-

gral therewith, of the central stay-blocks *e*, having slots to receive the edges of the fins or ribs, two or more encircling-straps having 15 interlocking ends, and the connecting-bolts *f*, substantially as set forth.

Signed by me this 22d day of August, A. D. 1889.

GEO. W. DITHRIDGE.
